UNITED STATES PATENT OFFICE.

LE ROY M. FULTON, OF CHICAGO, ILLINOIS.

PORTABLE SUPPORT.

Application filed September 13, 1923. Serial No. 662,493.

This invention relates generally to containers and supports therefor, and more particularly to an improved support characterized by the provision of means for permitting the adjustment of the support to different dimensions, more especially for the purpose of conveniently supporting and transporting objects of different sizes, such as containers illustrated herewith; this invention furthermore embodying improvements in a container particularly adapted for use with the support shown, for storing and transporting motion picture films.

It is customary to transport motion picture films from the exchange to the theatre in specially constructed fire and heat resistant containers, and as only one film of a series may be projected at a time, it is desirable that the remaining films be properly 15 safely housed while in the motion picture booth. To this end, the film case or container of this invention is provided, and in order that a motion picture booth may be properly equipped with means for supporting the film cases in a group, to which the film reels may be transferred when received, and extracted for use as required, I have provided the improved combined container and supporting device hereinafter 20 described in detail.

While the supporting device and the container are here illustrated and described as a unitary structure, for the purpose of convenience, it will be readily understood that 25 they may be used separately, and for purposes other than that shown, thus, this invention finds a wide field of utility for many purposes.

The principal objects and advantages 30 which characterize this invention reside in the provision of improved portable supporting means; the provision of improved variably dimensioned supporting means; the provision of improved variably dimensioned 35 readily portable supporting means; the provision of an improved supporting structure which is readily adapted for clampingly engaging an object to be supported; the provision of an improved combined support 40 and truck arranged to afford variable dimensions for engaging objects of various sizes; the provision of an improved device for supporting objects in different angular positions; the provision of an improved 45 combined supporting device and truck for variably angularly supporting and retaining ob-

jects of different dimensions; the provision of a device of the character described, which is capable of quick and facile assembly and dis-assembly; the provision of an improved 50 supporting device which embodies novel features of construction which provide for manufacture at low cost; and the provision of a device of the character described which, though capable of easy assembly, is rigid 55 when assembled and light and durable.

This invention is further characterized by the provision of an improved container and support therefor for rendering the container 60 readily accessible and easily transportable 50 from place to place; the provision of an improved combined portable support and improved container; the provision of an improved container for inflammable material, such as motion picture film reels, and which is provided with means facilitating the removal of the film reels therefrom; and the provision of an improved container embodying the foregoing and other improved 65 features and advantages, which is strong, and durable, heat and fire resistant, and capable of manufacture at low cost.

The foregoing and such other objects and advantages as may appear or be pointed out as this description proceeds are attained in 70 one structural embodiment of this invention, illustrated in the accompanying drawings in which:

Figure 1 is a fragmentary side elevational view of one form of this invention; 75

Figure 2 is an end elevational view, parts in section, of the same;

Figure 3 is a perspective view of a detail;

Figures 4 and 5 are fragmentary elevational and end views, respectively, of an 80 alternate form of this invention; and

Figure 6 is a perspective view of a detail.

Referring more particularly to the drawings, and first to Figures 1 to 3, inclusive, the supporting device includes the end frames F and F', which carry and retain the container A. The frames F and F' are arranged at the proper distance apart for the particular container or other article to be supported and retained by them. 85

The supporting frames F and F' are substantially identically constructed, and therefore I will describe but one of them, namely, that designated F.

The frame, in this form of the invention, 90 comprises the standards 5 and 6, preferably angle-iron and cut and formed to provide

a seat composed of the arms 7 and 8, at the top, and divergent legs 9 and 10 at the bottom.

The arms 7 and 8 are formed by cutting 5 through the end flanges of the angle-irons 5 and 6, as indicated at 11—11, and then bending said arms outwardly at approximately an angle of 45°. The legs 9 and 10 are similarly formed by cutting through the 10 same end flanges of the angle-irons, as indicated at 12—12, and then bending said legs outwardly. The legs are provided with foot 15 portions 13 and 14, by removing a generally V-shaped piece from said end flanges, at 14—14^a, and bending said foot portions into planes parallel to those of the standards 5 and 6. The lower ends of the foot portions are provided with base flanges 15 and 16, respectively, to which flanges are secured 20 casters 17.

The standards thus are formed each from a single bar of angle-iron, and said standards are fixed connected in space relationship by the provision of the flat transverse 25 top bar 18, riveted to the arms 7 and 8 at 19—19, intermediate flat bar 20, riveted at 21—21, and bottom relatively crossed flat bars 22 and 23, riveted each at 24—24 and 25—25 to the legs 9 and 10 and foot pieces, 30 respectively, a central rivet 26 fixedly connecting said crossed bars. Said rivets all pass through the end flanges of said angle bars.

In assembling the two frames, tie rods 27 35 and 28 are passed through the apertured projecting ends 29—29 of the bar 18, and thus lie outside the arms 7 and 8. Similar tie rods 30 and 31 pass through the upper portions of the crossed bars 22 and 23. The 40 frames F and F' are then drawn together into engagement with the ends or sides of a receptacle, such as A, which is supported by the seats 7 and 8. The projecting ends of the tie rods 27, 28 and 30 and 31 are 45 threaded to receive inner and outer retaining nuts 32 and 33.

The seats 7 and 8, as shown, lie at such an angularity that they readily receive 50 snugly two adjacent right-angularly disposed edges or corners of the polygonal receptacle A, but it will be obvious that, by varying the angularity of said seats receptacles having shapes other than that shown may be readily received and supported. 55 When the outer sets of nuts are tightened, the seats 7 and 8 of the end frames clampingly engage the adjacent portions of the receptacle, and then the inner nuts may be tightened in order to lock the frames. The 60 receptacle and frame thus are rigidly connected and form a substantially unitary readily portable structure.

The container of this invention preferably 65 comprises a substantially rectangular housing provided with heat and fire resisting

walls 34, said housing being divided, by partitions, equally heat resisting, into compartments 35, sufficiently capacious for reception of but one loaded film reel, seen at 36, Figure 2. Each of the compartments is 70 individually accessible and closed by the provision of doors 37—37, which latter having heat resisting walls 38, and are hinged at 39—39 to one corner of the container. The container is preferably placed in the 75 supporting device so that the hinges 39 are at the bottom, as shown.

On each of the doors, near the hinges thereof, there is provided a saddle 40 in the form of a loop, and hinged at 41 to its respective door. The saddle 40 serves to support and carry the film reel 36, so that, as the door is opened, the reel is raised out of the container and thus facilitates removal of the reel. Handles 42 are provided one on 85 each door.

The receptacle A is angularly supported as shown for the reason that by presenting an edge thereof upwardly it is impossible for one to carelessly leave anything, such 90 as a film reel on the top of the device, and thereby expose such a reel to fire should it occur in the immediate vicinity of the device. A rack for spare empty reels is afforded by the tie bars 30 and 31. Thus, the device not only affords a convenient readily portable truck for permanent assembly with a container for use in housing motion picture films and the like, but also contributes toward the attainment of absolute safety in 100 motion picture projection, and removes one of the common causes of fire in motion picture projection booths.

It is customary to construct the containers A with from three to eight compartments, and in the event that nine compartments are 105 desired, the purchaser may obtain a four and a five compartment container and use them jointly with the support. In this event, the joint between the two containers may be 110 supported and the containers kept even by placing the spanner, 43, shown in Figure 3, beneath the joint, said spanner comprising a flat right-angularly bent strip of metal, provided with lugs 44—44, which hook over 115 the tie rods 27 and 28. It will thus be seen that any number of containers, within reasonable limits, may be supported on the frame F and F', the capacity being only 120 dependent upon the length and strength of the tie rods and general structural endurance of the whole device.

Referring now to the alternate form of this invention illustrated in Figures 4 and 5, I provide a supporting structure in many respects similar to that shown in Figures 1 and 2, the principal feature of difference residing in that the alternate form of this invention is constructed for the purpose of supporting a polygonal object with its bot- 130

tom in a horizontal plane rather than angularly disposed.

Several types of film containers now on the market involve a gravity discharge feature, such as that shown in Figures 4 and 5 and designated B. There is provided in each compartment 45 what might be termed a false bottom, 46, arranged in an inclined plane, and the compartment opening at the side, with a sliding door 47 to close it. When the door is opened the film reel 48 rolls out. The invention, as constructed in Figures 1 and 2, might serve to support such a container as that shown in Figures 4 and 5, but the structure shown in the latter views is better adapted for this purpose, because the container should properly be supported level, and the arms 7 and 8 possibly would not have enough surface contact with the container if supported level thereon.

In this arrangement there are provided two end frames D and E, which are substantially identical in construction, therefore, I will describe but one of them.

The frame comprises a single angle-bar having one flange 49 thereof cut at 50-50 and 51-51, and bent to form divergent legs 52-52, divergent arms 53-53, and posts or standards 53^a, the legs 52 being further cut and bent to form foot portions 54-54. Casters 55-55 are secured to said foot portions.

The flange 49 of the angle bar is further more cut at 56 and when the angle bar is bent as shown affords a substantially horizontal transverse seat portion 57, which latter, on each frame, receive the adjacent end corners 58 of the container B.

From the foregoing it will be observed that the seat 57, arms, posts, and legs are all formed from a single angle-bar.

The structure thus provided is made more rigid by the provision of the transverse flat bars 59 and 60, the former being secured between the arms 53 by the tie rods 61-61 and their nuts 62-62, and the bar 60 being riveted at 63 to the posts 53^a. Abutment nuts 64 are arranged within the arms 53 on said tie rods 61, for locking the structure when assembled.

The legs 52 and foot portions 54 are fixedly connected and thereby maintained rigid by the provision of the crossed braces 65 and 66, which are riveted alternately to the legs and foot portions, as indicated at 67 and 68, respectively. A central rivet 69 fixedly connects said crossed braces at their inter-

section. A lower set of tie rods 70 extends between the upper portions of the braces 65 and 66, and nuts 71-71 serve to fix said tie rods.

The variable dimension feature of this device is similarly accomplished to that of the device shown in Figures 1 and 2, and therefore it is not necessary to repeat it here. It will be obvious that the supporting frames of both of the forms of this invention are interchangeable, and that the containers may be supported equally well by either of said devices. For this reason, I reserve the right to modify the structures shown within the spirit of this invention and the purview of the claims.

A spanner 43^a is employed in connection with the device of Figures 4 and 5, and performs the same function there as the spanner 43 performs in the device of Figures 1 and 2, the spanner 43^a having fingers 44^a which overlie the rods 61.

Having thus described my invention and illustrated its use, what I claim as new and desire to secure by Letters Patent is:—

1. In a supporting device, a pair of standards including angle bars notched at a plurality of points and bent at said notches to form complementary top divergent supporting portions, intermediate substantially parallel relatively spaced standards, divergent legs and spaced foot portions in planes substantially parallel with said intermediate standards, and transverse bars connected to said standards for spacing same apart whereby a polygonal container, may be supported in said top divergent supporting portions. 95

2. In a supporting device, a pair of standards including angle bars notched at a plurality of points and bent at said notches to form complementary top divergent supporting portions, intermediate substantially parallel relatively spaced standards, divergent legs and spaced foot portions in planes substantially parallel with said intermediate standards, horizontal transverse connecting and reinforcing bars arranged to connect said respective top divergent portions together, and crossed bars for connecting one each of said legs with the opposite foot portion, and said reinforcing bars having means attached thereto for forming an adjustable connection between two or more of said supporting devices. 110

In testimony whereof I hereunto affix my signature this 22nd day of August, 1922.

LE ROY M. FULTON.
